CLAIM

The ornamental design for a multi-tool, as shown and described.

DESCRIPTION

FIG. 1 is a perspective view of a multi-tool showing my new design;

FIG. 2 is a right side elevation view thereof;

FIG. 3 is a left side elevation view thereof;

FIG. 4 is a rear elevation view thereof;

FIG. 5 is a front elevation view thereof;

FIG. 6 is a top plan view thereof; and,

FIG. 7 is a bottom plan view thereof.

The broken lines represent environmental structure or boundaries that form no part of the claimed design.

1 Claim, 5 Drawing Sheets
